(57) **ABSTRACT**

According to one embodiment, an image forming apparatus includes a photosensitive drum, an exposure unit, a development unit, a toner supply motor, and a processor. The exposure unit exposes the photosensitive drum based on image data. The development unit forms a toner image on the photosensitive drum with toner supplied from a toner cartridge. The toner supply motor supplies the toner to the development unit from the toner cartridge. The processor detects toner emptiness when a toner supply ratio calculated based on an integrated value of a pixel count value of the image data and an integrated value of a driving time of the toner supply motor is less than a preset threshold.

**IMAGE FORMING APPARATUS AND
METHOD OF CONTROLLING IMAGE
FORMING APPARATUS**

FIELD

Embodiments described herein relate generally to an image forming apparatus and a method of controlling an image forming apparatus.

BACKGROUND

Image forming apparatuses receive toner from toner cartridges and perform image forming processes of forming toner images on photosensitive drums. The image forming apparatuses transfer the toner images on the photosensitive drums to print media.

In an image forming apparatus, a remaining toner amount in a toner cartridge is calculated based on a driving amount (a driving time) of a motor (a toner supply motor) that rotates a screw sending toner from the toner cartridge to the image forming apparatus. When the remaining toner amount is less than a near empty threshold, the image forming apparatus detects toner a near emptiness state indicating that little toner remains in the toner cartridge. The image forming apparatus includes a toner density sensor that detects a toner density in a development unit receiving toner from the toner cartridge. When a decrease in the toner density is detected, the image forming apparatus causes the toner supply motor to supply toner. When the toner density is not recovered despite an operation of the toner supply motor, the image forming apparatus detects toner emptiness indicating that the toner in the toner cartridge is empty.

However, in the determination of the toner emptiness based on the toner density, there is a problem that the number of prints from detection of the toner near emptiness state to detection of toner emptiness varies depending on a printing ratio of image data for printing.

DESCRIPTION OF THE DRAWINGS

FIG. 1 is a diagram illustrating a configuration example of an image forming apparatus according to an embodiment;

FIG. 2 is a diagram illustrating a configuration example of a part of an image forming unit;

FIG. 3 is a diagram illustrating an example of an operation of the image forming apparatus;

FIG. 4 is a diagram illustrating an example of an operation of the image forming apparatus;

FIG. 5 is a diagram illustrating an example of an operation of the image forming apparatus;

FIG. 6 is a diagram illustrating an example of an operation of the image forming apparatus; and

FIG. 7 is a diagram illustrating an example of an operation of the image forming apparatus.

DETAILED DESCRIPTION

In general, according to one embodiment, there is provided an image forming apparatus including a photosensitive drum, an exposure unit, a development unit, a toner supply motor, and a processor. The exposure unit exposes the photosensitive drum based on image data. The development unit forms a toner image on the photosensitive drum with toner supplied from a toner cartridge. The toner supply motor supplies the toner to the development unit from the toner cartridge. The processor detects toner emptiness when

2

a toner supply ratio calculated based on an integrated value of a pixel count value of the image data and an integrated value of a driving time of the toner supply motor is less than a preset threshold. In another embodiment, a toner emptiness detection system includes a processor that detects toner emptiness when a toner supply ratio calculated based on an integrated value of a pixel count value of image data used to expose a photosensitive drum and an integrated value of a driving time of a toner supply motor that supplies toner to a development component from a toner cartridge to form a toner image on the photosensitive drum with toner is less than a preset threshold.

Hereinafter, an image forming apparatus and a method of controlling an image forming apparatus according to an embodiment will be described with reference to the drawings.

FIG. 1 is a diagram illustrating a configuration example of an image forming apparatus 1 according to the embodiment.

The image forming apparatus 1 is, for example, a multi-function printer (MFP) that performs various processes such as image forming while conveying a recording medium such as a printing medium. The image forming apparatus 1 is, for example, a solid-state scanning type printer (for example, an LED printer) that scans an LED array performing various processes such as image forming while conveying a recording medium such as a printing medium.

For example, the image forming apparatus 1 has a configuration in which toner is received from a toner cartridge 2 and an image is formed on a printing medium using the received toner. The toner may be monochromatic toner or may be color toner of, for example, cyan, magenta, yellow, and black.

As illustrated in FIG. 1, the image forming apparatus 1 includes a casing 11, a communication interface 12, a system controller 13, a display unit 14, an operation interface 15, a plurality of sheet trays 16, a discharge tray 17, a conveyance unit 18, an image forming unit 19, and a fixing unit 20.

The casing 11 is the body of the image forming apparatus 1. The casing 11 accommodates the communication interface 12, the system controller 13, the display unit 14, the operation interface 15, the plurality of sheet trays 16, the discharge tray 17, the conveyance unit 18, the image forming unit 19, and the fixing unit 20.

The communication interface 12 is an interface used to communicate with another device. The communication interface 12 is used to communicate with, for example, a host device (an external device). The communication interface 12 is configured by, for example, a LAN connector or the like. The communication interface 12 may perform wireless communication with another device in conformity with a standard such as Bluetooth (registered trademark) or Wi-Fi (registered trademark).

The system controller 13 controls the image forming apparatus 1. The system controller 13 includes, for example, a processor 21 and a memory 22.

The processor 21 is an arithmetic operation element that performs an arithmetic process. The processor 21 is, for example, a CPU. The processor 21 performs various processes based on data such as a program stored in the memory 22. The processor 21 functions as a control unit capable of performing various operations by executing the program stored in the memory 22.

The memory 22 is a storage medium that stores a program and data or the like used for the program. The memory 22 also functions as a working memory. That is, the memory 22

temporarily stores data which is being processed by the processor 21 and a program or the like executed by the processor 21.

The processor 21 performs various kinds of information processing by executing a program stored in the memory 22. For example, the processor 21 generates a printing job based on an image acquired from an external device via, for example, the communication interface 12. The processor 21 stores the generated printing job in the memory 22.

The printing job includes image data indicating an image which is formed on a printing medium P. The image data may be data for forming an image on one printing medium P or may be data for forming an image on a plurality of printing media P. Further, the printing job includes information indicating color printing or monochrome printing.

The processor 21 functions as a controller (an engine controller) that controls operations of the conveyance unit 18, the image forming unit 19, and the fixing unit 20 by executing a program stored in the memory 22. That is, the processor 21 controls conveying of the printing medium P by the conveyance unit 18, controls forming of an image on the printing medium P by the image forming unit 19, and controls fixing of an image on the printing medium P by the fixing unit 20.

The image forming apparatus 1 may include an engine controller apart from the system controller 13. In this case, the engine controller controls conveying of the printing medium P by the conveyance unit 18, controls forming of an image on the printing medium P by the image forming unit 19, and controls fixing of an image on the printing medium P by the fixing unit 20. In this case, the system controller 13 supplies information necessary for control in the engine controller to the engine controller.

The display unit 14 includes a display that displays a screen in accordance with a video signal input from a display control unit such as a graphic controller (not illustrated) or the system controller 13. For example, a screen for various settings of the image forming apparatus 1 and information such as a remaining toner amount are displayed on the display of the display unit 14.

The operation interface 15 is connected to an operation member (not illustrated). The operation interface 15 supplies an operation signal in response to an operation of the operation member to the system controller 13. The operation member is, for example, a touch sensor, a numeric key, a power key, a sheet feeding key, various function keys, or a keyboard. The touch sensor acquires information indicating a position designated in a certain region. When the touch sensor is configured as a touch panel integrated with the display unit 14, a signal indicating a position touched on a screen displayed on the display unit 14 is input to the system controller 13.

The plurality of sheet trays 16 are cassettes that accommodate the printing media P. The sheet tray 16 can supply the printing medium P from the outside of the casing 11. For example, the sheet tray 16 can be taken out from the casing 11.

The discharge tray 17 is a tray that supports the printing medium P discharged from the image forming apparatus 1.

Next, a configuration of the image forming apparatus 1 in which the printing media P is conveyed will be described.

The conveyance unit 18 is a mechanism that conveys the printing medium P in the image forming apparatus 1. As illustrated in FIG. 1, the conveyance unit 18 includes a plurality of conveyance paths. For example, the conveyance unit 18 includes a paper feed conveyance path 31 and a discharge conveyance path 32.

The paper feed conveyance path 31 and the discharge conveyance path 32 each include a plurality of motors, a plurality of rollers, and a plurality of guides (none of which are illustrated). The plurality of motors rotate the rollers synchronized with rotation of shafts by rotating the shafts under the control of the system controller 13. The plurality of rollers are rotated to move the printing medium P. The plurality of guides control a conveyance direction of the printing medium P.

10 The paper feed conveyance path 31 takes the printing medium P from the sheet tray 16 and supplies the taken printing medium P to the image forming unit 19. The paper feed conveyance path 31 includes a pickup roller 33 corresponding to each sheet tray. Each pickup roller 33 takes the 15 printing medium P of each sheet tray 16 into the paper feed conveyance path 31.

The discharge conveyance path 32 is a conveyance path along which the printing medium P on which an image is formed is discharged from the casing 11. The printing 20 medium P discharged by the discharge conveyance path 32 is supported by the discharge tray 17.

Next, the image forming unit 19 will be described.

The image forming unit 19 forms an image on the printing medium P. Specifically, the image forming unit 19 forms an 25 image on the printing medium P based on a printing job generated by the processor 21.

The image forming unit 19 includes a plurality of load units 41, a plurality of process units 42, a plurality of exposure units 43, and a plurality of transfer mechanisms 44.

30 The image forming unit 19 includes the load unit 41 and the exposure unit 43 for each process unit 42. Since the plurality of process units 42, the plurality of load units 41, and the plurality of exposure units 43 each have the same configurations, one process unit 42, one load unit 41, and one 35 exposure unit 43 will be described as examples.

FIG. 2 is a diagram illustrating a configuration example of a part of the image forming unit 19.

First, the toner cartridge 2 mounted on the load unit 41 will be described.

40 As illustrated in FIG. 2, the toner cartridge 2 includes a toner accommodation container 51 and a toner sending mechanism 52. The toner cartridge 2 includes an IC chip (not illustrated).

The toner accommodation container 51 is a container that 45 accommodates toner.

The toner sending mechanism 52 is a mechanism that sends toner in the toner accommodation container 51. The toner sending mechanism 52 is, for example, a screw that is provided in the toner accommodation container 51 and is 50 rotated to send the toner.

The IC chip includes a memory that stores various kinds of control data in advance. The control data is, for example, an “identification code” and a “near empty threshold.” The “identification code” indicates a type and a model number of the toner cartridge 2. The “near empty threshold” is a threshold used for the image forming apparatus 1 to determine whether a remaining toner amount in the toner cartridge 2 is small.

55 Next, the load unit 41 on which the toner cartridge 2 is mounted will be described.

As illustrated in FIG. 2, the load unit 41 is a module on which the toner cartridge 2 filled with each toner is mounted. Each of the plurality of load units 41 includes a space in which the toner cartridge 2 is mounted and the toner supply 60 motor 61. Each of the plurality of load units 41 includes a communication interface (not illustrated) that connects an IC chip of the toner cartridge 2 to the system controller 13.

The toner supply motor 61 drives the toner sending mechanism 52 of the toner cartridge 2 under the control of the processor 21. The toner supply motor 61 is connected to the toner sending mechanism 52 of the toner cartridge 2 when the toner cartridge 2 is loaded on the load unit 41. The toner supply motor 61 is electrified under the control of the processor 21 and rotates a shaft to drive the toner sending mechanism 52 of the toner cartridge 2. The toner supply motor 61 supplies the toner in the toner accommodation container 51 to a development unit to be described below by driving the toner sending mechanism 52.

Next, the process unit 42 will be described.

The process unit 42 is configured to form a toner image. For example, the plurality of process units 42 are provided for each kind of toner. For example, the plurality of process units 42 correspond to color toner of cyan, magenta, yellow, and black, respectively. Specifically, the toner cartridge 2 that has different color toner is connected to each process unit 42.

As illustrated in FIG. 2, the process unit 42 includes a photosensitive drum 71, a cleaner 72, an electrostatic charger 73, and a development unit 74.

The photosensitive drum 71 is a photoreceptor that has a cylindrical drum and a photosensitive layer formed on the outer circumferential surface of the drum. The photosensitive drum 71 is rotated at a constant speed by a driving mechanism (not illustrated).

The cleaner 72 removes toner remaining on the surface of the photosensitive drum 71.

The electrostatic charger 73 uniformly charges the surface of the photosensitive drum 71. For example, the electrostatic charger 73 charges the photosensitive drum 71 with a uniform negative potential by applying a voltage to the photosensitive drum 71 using a charging roller. The charging roller is rotated with rotation of the photosensitive drum 71 in a state in which the charging roller adds a predetermined pressure to the photosensitive drum 71.

The development unit 74 is a device that attaches the toner to the photosensitive drum 71. The development unit 74 includes a developer container 81, a stirring mechanism 82, a development roller 83, a doctor blade 84, and an auto toner control (ATC) sensor 85.

The developer container 81 is a container that accommodates developer including toner and carriers. The developer container 81 receives the toner sent from the toner cartridge 2 by the toner sending mechanism 52. The carriers are accommodated in the developer container 81 when the development unit 74 is manufactured.

The stirring mechanism 82 is driven by a motor (not illustrated) and stirs the toner and the carriers in the developer container 81.

The development roller 83 is rotated in the developer container 81 to attach the developer to the surface.

The doctor blade 84 is a member that is disposed to be away from the surface of the development roller 83 at a predetermined interval. The doctor blade 84 removes a part of the developer attached to the surface of the rotating development roller 83. Thus, a layer of the developer with a thickness in accordance with the interval between the doctor blade 84 and the surface of the development roller 83 is formed on the surface of the development roller 83.

The ATC sensor 85 is, for example, a magnetic flux sensor that includes, for example, a coil and detects a voltage value generated in the coil. A voltage detected by the ATC sensor 85 is changed by density of a magnetic flux from the toner in the developer container 81. That is, the system controller 13 can determine a density ratio (simply referred to as

density) of the toner remaining in the developer container 81 to the carriers based on the voltage detected by the ATC sensor 85.

Next, the exposure unit 43 will be described.

The exposure unit 43 includes a plurality of light-emitting elements. The exposure unit 43 forms a latent image on the photosensitive drum 71 by radiating light from the light-emitting elements to the charged photosensitive drum 71. The light-emitting element is, for example, a light-emitting diode (LED) or a laser diode (LD). One light-emitting element is configured to radiate light at one point on the photosensitive drum 71. The plurality of light-emitting elements are arranged in a main scanning direction which is a direction parallel to the rotation axis of the photosensitive drum 71.

The exposure unit 43 forms a latent image corresponding to one line on the photosensitive drum 71 by causing the plurality of light-emitting elements arranged in the main scanning direction to radiate light onto the photosensitive drum 71. Further, the exposure unit 43 forms a latent image of a plurality of lines by continuously radiating light onto the rotating photosensitive drum 71.

In the foregoing configuration, an electrostatic latent image is formed when the light is radiated from the exposure unit 43 to the surface of the photosensitive drum 71 charged by the electrostatic charger 73. When the layer of the developer formed on the surface of the development roller 83 approaches the surface of the photosensitive drum 71, the toner contained in the developer is attached to the latent image formed on the surface of the photosensitive drum 71. In this way, a toner image is formed on the surface of the photosensitive drum 71.

Next, the transfer mechanism 44 will be described.

The transfer mechanism 44 transfers the toner image formed on the surface of the photosensitive drum 71 to the printing medium P.

As illustrated in FIGS. 1 and 2, the transfer mechanism 44 includes, for example, a primary transfer belt 91, a secondary transfer counter roller 92, a plurality of primary transfer rollers 93, and a secondary transfer roller 94.

The primary transfer belt 91 is an endless belt that is wound around the secondary transfer counter roller 92 and a plurality of winding rollers. An inner surface (an inner circumferential surface) of the primary transfer belt 91 comes into contact with the secondary transfer counter roller 92 and the plurality of winding rollers and an outer surface (an outer circumferential surface) thereof faces the photosensitive drum 71 of the process unit 42.

The secondary transfer counter roller 92 is rotated by a motor (not illustrated). The secondary transfer counter roller 92 is rotated to convey the primary transfer belt 91 in a predetermined conveyance direction. The plurality of winding rollers are rotatable freely. The plurality of winding rollers are rotated with movement of the primary transfer belt 91 by the secondary transfer counter roller 92.

The plurality of primary transfer rollers 93 bring the primary transfer belt 91 into contact with the photosensitive drum 71 of the process unit 42. The plurality of primary transfer rollers 93 are provided to correspond to the photosensitive drums 71 of the plurality of process units 42. Specifically, the plurality of primary transfer rollers 93 are provided at positions facing the corresponding photosensitive drums 71 of the process units 42 with the primary transfer belt 91 interposed therebetween. The primary transfer rollers 93 come into contact with the inner circumferential surface of the primary transfer belt 91 to displace the primary transfer belt 91 to the sides of the photosensitive

drums 71. Thus, the primary transfer rollers 93 bring the outer circumferential surface of the primary transfer belt 91 into contact with the photosensitive drums 71.

The secondary transfer roller 94 is provided at a position facing the primary transfer belt 91. The secondary transfer roller 94 comes into contact with the outer circumferential surface of the primary transfer belt 91 and adds a pressure. Thus, a transfer nip in which the secondary transfer roller 94 comes into close contact with the outer circumferential surface of the primary transfer belt 91 is formed. The secondary transfer roller 94 presses the printing medium P passing through the transfer nip against the outer circumferential surface of the primary transfer belt 91 when the printing medium P passes through the transfer nip.

The secondary transfer roller 94 and the secondary transfer counter roller 92 are rotated to convey the printing medium P supplied from the paper feed conveyance path 31 in a state in which the printing medium P is interposed therebetween. Thus, the printing medium P passes through the transfer nip.

In the foregoing configuration, when the outer circumferential surface of the primary transfer belt 91 comes into contact with the photosensitive drum 71, a toner image formed on the surface of the photosensitive drum is transferred to the outer circumferential surface of the primary transfer belt 91. As illustrated in FIG. 1, when the image forming unit 19 includes the plurality of process units 42, the primary transfer belt 91 receives the toner images from the photosensitive drums 71 of the plurality of process units 42. The toner images transferred to the outer circumferential surface of the primary transfer belt 91 are conveyed to the transfer nip in which the secondary transfer roller 94 comes into close contact with the primary transfer belt 91 by the primary transfer belt 91. When the printing medium P is in the transfer nip, the toner images transferred to the outer circumferential surface of the primary transfer belt 91 are transferred to the printing medium P in the transfer nip.

Next, a configuration related to fixing in the image forming apparatus 1 will be described.

The fixing unit 20 fixes a toner image by melting the toner transferred to the printing medium P. The fixing unit 20 operates under the control of the system controller 13. The fixing unit 20 includes a heating member that heats the printing medium P and a pressurization member that pressurizes the printing medium P. For example, the heating member is a heat roller 95. For example, the pressurization member is a press roller 96.

The heat roller 95 is a fixing rotator that is rotated by a motor (not illustrated). The heat roller 95 includes a core that is hollow and is formed of a metal and an elastic layer that is formed on the outer circumference of the core. The heat roller 95 is heated at a high temperature by a heater disposed on the inner side of the hollow core. The heater is, for example, a halogen heater. The heater may be an induction heating (IH) heater that heats the core by electromagnetic induction.

The press roller 96 is provided at a position facing the heat roller 95. The press roller 96 includes a core that has a predetermined outer diameter and is formed of a metal and an elastic layer that is formed on the outer circumference of the core. The press roller 96 applies a pressure to the heat roller 95 in accordance with stress added from a tension member (not illustrated). When the pressure is applied from the press roller 96 to the heat roller 95, a nip (a fixing nip) in which the press roller 96 comes into close contact with the heat roller 95 is formed. The press roller 96 is rotated by a motor (not illustrated). The press roller 96 is rotated to move

the printing medium P entering the fixing nip and press the printing medium P against the heat roller 95.

In the foregoing configuration, the heat roller 95 and the press roller 96 apply heat and pressure to the printing medium P passing through the fixing nip. Thus, the toner image is fixed to the printing medium P passing through the fixing nip. The printing medium P passing through the fixing nip is introduced into the discharge conveyance path 32 to be discharged to the outside of the casing 11. The fixing unit 20 is not limited to the foregoing configuration. The fixing unit 20 may be configured in conformity with an on-demand scheme of giving heat to the printing medium P to which a toner image is transferred via a film-like member to melt and fix the toner.

Next, control of the image forming apparatus 1 by the system controller 13 will be described.

FIG. 3 is a flowchart illustrating a process related to toner by the image system controller 13. The processor 21 of the system controller 13 performs a process of FIG. 3 whenever printing is performed. For example, the processor 21 may perform the process of FIG. 3 whenever a single print is performed, may perform the process of FIG. 3 whenever a single printing job is completed, or may perform the process of FIG. 3 whenever a plurality of prints are performed.

The processor 21 integrates a pixel amount (a pixel count value) based on a pixel value of printing image data (ACT11). For example, the processor 21 integrates the pixel count value based on the pixel value of the printing image data. Specifically, the processor 21 converts the image data into an image signal for driving each exposure unit 43. The processor 21 integrates the pixel count value for each color of the toner based on the image signal after the toner cartridge 2 is replaced. The processor 21 stores the pixel count value in, for example, the memory 22. The processor 21 updates the pixel count value on the memory 22 by integrating the pixel count value.

The processor 21 integrates a driving amount (a driving time) of the toner supply motor 61 after the toner cartridge 2 is replaced (ACT12). For example, the processor 21 stores the driving time in the memory 22. The processor 21 updates the driving time on the memory 22 by integrating the driving time.

The processor 21 calculates a remaining toner amount indicating a remaining amount of toner in the toner accommodation container 51 of the toner cartridge 2 (ACT13). The processor 21 stores the calculated remaining toner amount in, for example, the memory 22. The processor 21 calculates the remaining toner amount based on, for example, the integrated value of the driving time.

The processor 21 calculates a toner supply amount based on, for example, the integrated value of the driving time. The toner supply amount is a ratio of the amount of toner supplied from the toner cartridge 2 to the development unit 74 to an initial value of the amount of toner in the toner accommodation container 51 of the toner cartridge 2. An initial value of the remaining toner amount on the memory 22 is 100[%]. The processor 21 updates the remaining toner amount [%] on the memory 22 based on the calculated toner supply amount [%] and the remaining toner amount [%] on the memory 22.

Specifically, the processor 21 calculates a rotation amount based on a rotation number (a rotation amount) of the shaft of the toner supply motor 61 per driving time and the integrated value of the driving time of the toner supply motor 61. The processor 21 calculates a toner supply amount [%] in accordance with the integrated value of the driving time based on the calculated rotation amount and the toner

supply amount per rotation amount. The processor 21 calculates a present remaining toner amount [%] in the toner cartridge 2 by subtracting the calculated toner supply amount [%] from 100 [%] which is the initial value.

The rotation number (the rotation amount) of the shaft of the toner supply motor 61 per driving time and the toner supply amount per rotation amount are determined in advance in consideration of an average value of evaluation results for each model of the image forming apparatus 1 and the toner cartridge 2 and a variation in the image forming apparatus 1.

The processor 21 causes the display unit 14 to display the remaining toner amount on the memory 22 (ACT14). The processor 21 may cause the display unit 14 to display the remaining toner amount in accordance with an input operation or may notify another device of the remaining toner amount via the communication interface 12.

The processor 21 performs a toner supply process to be described below (ACT15). In the toner supply process, the processor 21 determines whether it is necessary to supply the toner, detects the toner emptiness, and drives the toner supply motor 61.

The processor 21 determines whether the calculated remaining toner amount is equal to or greater than a preset near empty threshold (ACT16). When the processor 21 determines that the calculated remaining toner amount is equal to or greater than the preset near empty threshold (YES in ACT16), the process proceeds to ACT22 to be described below.

When the processor 21 determines that the calculated remaining toner amount is equal to or less than the preset near empty threshold (NO in ACT16), the processor 21 detects near emptiness (ACT17). The near emptiness indicates a state in which few toner remains in the toner cartridge 2.

When the processor 21 detects the near emptiness, the processor 21 causes the display unit 14 to output information prompting preparation to replace the toner cartridge (display toner near emptiness) (ACT18).

The processor 21 performs a toner supply ratio calculation process to be described below (ACT19). In the toner supply ratio calculation process, the processor 21 calculates a toner supply ratio and detects the toner emptiness.

Subsequently, the processor 21 determines whether toner emptiness is confirmed (ACT20). The processor 21 determines whether the toner emptiness is confirmed based on the detection result of the toner emptiness in the toner supply process and the detection result of the toner emptiness in the toner supply ratio calculate process. For example, when the processor 21 detects the toner emptiness in either the toner supply process or the toner supply ratio calculation process, the processor 21 determines that the toner emptiness is confirmed.

When the processor 21 determines that the toner emptiness is not confirmed (NO in ACT20), the process proceeds to ACT22.

Conversely, when the processor 21 determines that the toner emptiness is confirmed (YES in ACT20), the processor 21 causes the display unit 14 to output information prompting replacement of the toner cartridge 2 (display the toner emptiness) (ACT21), and then the process proceeds to ACT22.

The processor 21 determines whether the process ends (ACT22). For example, when an operation of ending an operation of the image forming apparatus 1 is performed or there is no subsequent printing, the processor 21 determines that the process ends. When there is subsequent printing and

the processor 21 determines that the process does not end (NO in ACT22), the process proceeds to ACT11. Thus, whenever printing is performed, the processor 21 repeatedly performs the process from ACT11 to ACT22. Conversely, when the processor 21 determines that the process ends (YES in ACT22), the process of FIG. 3 ends.

Next, the toner supply process will be described.

FIG. 4 is a flowchart illustrating an example of a toner supply process. That is, the process of FIG. 4 is equivalent to the process of ACT15 in FIG. 3.

The processor 21 acquires toner density based on a detection result of the ATC sensor 85 (ACT31). A voltage detected by the ATC sensor 85 varies depending on density of a magnetic flux from the toner in the developer container 81. The processor 21 calculates toner density with respect to the carriers of the developer container 81 based on the voltage detected by the ATC sensor 85 and a preset coefficient or function.

The processor 21 compares the toner density [%] with a preset standard density [%] (ACT32). The standard density is toner density necessary to operate the development unit 74 stably and is stored in advance in, for example, the memory 22. For example, the processor 21 calculates a difference between the toner density acquired in ACT31 and the standard density.

The processor 21 determines whether a decrease amount of the toner density is equal to or greater than 1.0[%] (ACT33). That is, the processor 21 determines whether the toner density—the standard density is equal to or greater than -1.0[%]. In other words, the processor 21 determines whether the toner density in the developer container 81 is equal to or greater than a predetermined threshold.

When the processor 21 determines that the decrease amount of the toner density is not equal to or greater than 1.0[%] (NO in ACT33), the process of FIG. 4 ends.

When the processor 21 determines that the decrease amount of the toner density is equal to or greater than 1.0[%] (YES in ACT33), the processor 21 determines whether the toner supply operation continues for a predetermined time or more (ACT34). That is, the processor 21 determines whether the toner supply motor 61 is operating and a time in which the toner supply motor 61 is driven is equal to or greater than a predetermined time.

When the processor 21 determines that the toner supply operation does not continue for the predetermined time or more (NO in ACT34), the processor 21 performs the toner supply operation (ACT35), and then the process proceeds to ACT31. That is, the processor 21 drives the toner supply motor 61 to supply the toner from the toner cartridge 2 to the development unit 91. The processor 21 continues the toner supply operation, for example, until the decrease amount of the toner density is less than 1.0[%] or a predetermined time passes.

When the processor 21 determines that the toner supply operation continues for the predetermined time or more (YES in ACT34), the processor 21 determines whether the decrease amount of the toner density is equal to or greater than 1.5 [%] (ACT36). That is, the processor 21 determines whether toner density—the standard density is equal to or greater than -1.5[%].

When the processor 21 determines that the decrease amount of the toner density is not equal to or greater than 1.5[%] (NO in ACT36), the process of FIG. 4 ends.

When the processor 21 determines that the decrease amount of the toner density is equal to or greater than 1.5[%] (YES in ACT36), the processor 21 detects the toner emptiness (ACT37), and then the process of FIG. 4 ends. That is,

11

when the toner density is not recovered despite performing the toner supply operation for the predetermined time, the processor 21 detects the toner emptiness.

Next, the toner supply ratio calculation process will be described.

FIG. 5 is a flowchart illustrating a toner supply ratio calculation process. That is, the process of FIG. 5 is equivalent to the process of ACT19 in FIG. 3.

The processor 21 determines whether the interval number of prints is equal to or greater than a preset threshold (ACT41). The interval number of prints indicates the number of printed documents. The processor 21 resets the interval number of prints whenever the interval number of prints is equal to or greater than the threshold.

When the processor 21 determines that the interval number of prints is less than the preset threshold (NO in ACT41), the process of FIG. 5 ends.

When the processor 21 determines that the interval number of prints is equal to or greater than the preset threshold (YES in ACT41), the processor 21 resets the interval number of prints and performs the processes from ACT42 to ACT44 to be described below.

When the processor 21 determines that the interval number of prints is equal to or greater than the preset threshold (YES in ACT41), the processor 21 calculates a toner supply ratio during printing of the interval number of prints (ACT42). That is, the processor 21 calculates the toner supply ratio whenever the interval number of prints reaches the preset threshold.

The toner supply ratio is a ratio of a toner usage amount to a toner supply amount until the interval number of prints is reset and reaches the threshold (hereinafter simply referred to as a supply ratio calculation interval). The toner usage amount can be estimated from a pixel count value. The toner supply amount can be estimated from a driving time of the toner supply motor 61. The processor 21 calculates a toner supply ratio based on an integrated value of the pixel count value and the integrated value of the driving time of the toner supply motor 61. For example, the processor 21 calculates a toner supply ratio based on an increment of the integrated value of the pixel count value at the supply ratio calculation interval and an increment of the integrated value of the driving time of the toner supply motor 61 at the supply ratio calculation interval. More specifically, the processor 21 calculates a value obtained by dividing a normalized value of the increment of the integrated value of the pixel count value by a normalized value of the increment of the integrated value of the driving time of the toner supply motor 61 as the toner supply ratio. That is, the toner supply ratio is a ratio of the driving time of the toner supply motor 61 to the pixel count value.

The processor 21 determines whether the calculated toner supply ratio is equal to or less than a preset toner supply ratio threshold (ACT43). The toner supply ratio threshold is determined in advance in consideration of an average value of evaluation results for each model of the image forming apparatus 1 and the toner cartridge 2 and a variation in the image forming apparatus 1. The toner supply ratio threshold is stored in advance in, for example, the memory 22.

When the processor 21 determines that the toner supply ratio is not equal to or less than the toner supply ratio threshold (NO in ACT43), the process of FIG. 5 ends.

When the processor 21 determines that the toner supply ratio is equal to or less than the toner supply ratio threshold (YES in ACT43), the processor 21 detects the toner emptiness (ACT44), and then the process of FIG. 5 ends. That is, the processor 21 detects the toner emptiness when the

12

driving time of the toner supply motor 61 becomes longer than the pixel count value and the toner supply ratio is equal to or less than the toner supply ratio threshold.

FIG. 6 is a diagram illustrating a relation among a toner supply ratio, the number of prints, and a printing ratio. The vertical axis of FIG. 6 represents the toner supply ratio. The horizontal axis of FIG. 6 represents the number of prints. Each graph in FIG. 6 indicates each of different printing ratios. FIG. 6 illustrates a relation between the number of prints before and after a timing at which there is no substantial toner in the toner cartridge 2 (the number of print=0) and the toner supply ratio. In the example of FIG. 6, the toner supply ratio threshold=100 is set.

As illustrated in FIG. 6, the toner supply ratio decreases in proportion to an increase in the number of prints. That is, the toner supply ratio decreases in proportion to a decrease in the toner in the toner cartridge 2. This is because a toner supply amount per driving amount of the toner sending mechanism 52 of the toner cartridge 2 decreases with a decrease in the toner in the toner cartridge 2 and a driving time of the toner supply motor 61 for supplying the same amount of toner becomes long.

The degree of decrease in the toner supply ratio differs depending on a printing ratio. Specifically, the larger the printing ratio is, the larger the decrease in the toner supply ratio per number of prints is, and the smaller the printing ratio is, the smaller the decrease in the toner supply ratio per number of prints is. Therefore, for example, when the printing ratio of a printing image is equal to or less than 10%, the toner supply ratio is less than the toner supply ratio threshold in printing of 100 sheets from a state of no substantial toner. For example, when the printing ratio of a printing image is equal to or less than 1%, the toner supply ratio is not less than the toner supply ratio threshold in printing of 100 sheets from a state of no substantial toner and is less than the toner supply ratio threshold in printing of 150 sheets. For example, when the printing ratio of a printing image is equal to or greater than 20%, the toner emptiness is detected based on toner density before the toner supply ratio reaches the toner supply ratio threshold.

FIG. 7 is a diagram illustrating a relation between a toner supply ratio scheme of detecting toner emptiness based on a toner supply ratio and a toner density sensor detection scheme of detecting toner emptiness based on toner density. The vertical axis of FIG. 7 represents the number of prints until the toner emptiness is detected from a state of no substantial toner. The horizontal axis of FIG. 7 represents a printing ratio.

As illustrated in FIG. 7, in the toner density sensor detection scheme, the number of prints tends to increase at a low printing ratio until the toner emptiness is detected. This is because, at a low printing ratio, a time is necessary until no toner is supplied from the toner cartridge 2 and the toner density in the development container 81 decreases.

In the toner supply ratio scheme, on the other hand, the number of prints tends to be stable irrespective of the printing ratio until the toner emptiness is detected. This is because, in the toner supply ratio scheme, the integrated value of the driving time of the toner supply motor 61 increases with respect to the integrated value of the pixel count value irrespective of a state of the development container 81 and the toner supply ratio considerably decreases in a state of no substantial toner. That is, in the toner density sensor detection scheme, the toner emptiness can be detected at a timing faster than in the toner density sensor detection scheme at a low printing ratio at which the detection of the toner emptiness is late.

13

As described in ACT20 of FIG. 3, the processor 21 determines that the toner emptiness is confirmed when the processor 21 detects the toner emptiness in either the toner density sensor detection scheme or the toner supply ratio scheme. Thus, at a low printing ratio (less than a printing ratio=10[%] in the example of FIG. 7), detection of the toner emptiness in conformity with the toner supply ratio scheme is adopted. At a high printing ratio (equal to or greater than the printing ratio=10[%] in the example of FIG. 7), detection of the toner emptiness in conformity with the toner density sensor detection scheme is adopted.

As described above, the image forming apparatus 1 includes the photosensitive drum 71, the exposure unit 43 that exposes the photosensitive drum 71 based on the image data, the development unit 74 that forms a toner image on the photosensitive drum 71 with toner supplied from the toner cartridge 2, the toner supply motor 61 that supplies the toner from the toner cartridge 2 to the development unit 74, and the processor 21. The processor 21 calculates a toner supply ratio based on an integrated value of a pixel count value of image data and an integrated value of a driving time of the toner supply motor. The processor 21 detects toner emptiness when the toner supply ratio is less than the preset threshold.

Thus, the image forming apparatus 1 can prevent the number of prints from detection of the toner near emptiness until detection of the toner emptiness from varying depending on a printing ratio of printing image data. In particular, when the printing ratio of the printing image data is a low printing ratio, the image forming apparatus 1 can prevent the number of prints until detection of the toner emptiness from increasing. As a result, it is possible to prevent a load from being applied to the development unit 74 since the development unit 74 operates for a long time in a state of low toner density in the development container 81 of the development unit 74.

In the foregoing embodiment, the processor 21 calculates the value obtained by dividing the integrated value of the pixel count value by the integrated value of the driving time of the toner supply motor 61 as the toner supply ratio, as described above, but an exemplary embodiment is not limited to this configuration. The processor 21 may calculate a value obtained by dividing the integrated value of the driving time of the toner supply motor 61 by the integrated value of the pixel count value as a toner supply ratio.

In the foregoing embodiment, the processor 21 calculates the integrated value of the pixel count value and the integrated value of the driving time of the toner supply motor 61 whenever a preset number of sheets are printed as the interval number of prints, as described above, but an exemplary embodiment is not limited to this configuration. The processor 21 may have any configuration as long as the integrated value of the pixel count value and the integrated value of the driving time of the toner supply motor 61 are calculated at each preset process interval. For example, the process interval may be determined based on the integrated value of the pixel count value or the integrated value of the driving time of the toner supply motor 61. That is, ACT41 of FIG. 5 may be replaced with determination of, for example, "whether the integrated value of the pixel count value increases by a preset value" or "whether the integrated value of the driving time of the toner supply motor 61 increases by a preset value."

For example, when the process interval is determined in accordance with the integrated value of the pixel count value, the processor 21 calculates an increment of the integrated value of the driving time of the toner supply

14

motor 61 whenever the integrated value of the pixel count value increases by a preset value. That is, the processor 21 calculates the toner supply ratio based on an increment of the integrated value of the driving time of the toner supply motor 61 while the integrated value of the pixel count value increases by a preset value.

For example, when the process interval is determined in accordance with the integrated value of the driving time of the toner supply motor 61, the processor 21 calculates an increment of the integrated value of the pixel count value whenever the integrated value of the driving time of the toner supply motor 61 increases by a preset value. That is, the processor 21 calculates the toner supply ratio based on an increment of the integrated value of the pixel count value while the integrated value of the driving time of the toner supply motor 61 increases by a preset value.

In the foregoing embodiment, the remaining toner amount in the toner accommodation container 51 of the toner cartridge 2 is calculated based on the integrated value of the driving time of the toner supply motor 61 after the toner cartridge 2 is replaced, as described above, but an exemplary embodiment is not limited to this configuration. The processor 21 may calculate a toner remaining amount in the toner accommodation container 51 of the toner cartridge 2 based on the integrated value of the pixel count value after the toner cartridge 2 is replaced.

In the foregoing embodiment, the processor 21 detects the toner near emptiness based on the near empty threshold and the remaining toner amount which is calculated based on the integrated value of the driving time of the toner supply motor 61, as described above, but an exemplary embodiment is not limited to this configuration. The processor 21 may detect toner near emptiness based on the toner supply ratio.

For example, the processor 21 calculates a toner supply ratio for each printing of the interval number of prints (a predetermined process interval) irrespective of detecting the toner near emptiness based on the remaining toner amount. The processor 21 detects the toner near emptiness when the calculated toner supply ratio is less than a preset threshold (a near empty threshold compared with the toner supply ratio). Further, the processor 21 detects the toner emptiness when the calculated toner supply ratio is less than a preset threshold (the foregoing toner supply ratio threshold).

The functions described in each of the above-described embodiments can be realized not only using hardware but also using software by reading a program describing each function to a computer. Each function may be configured by appropriately selecting software or hardware.

While certain embodiments have been described, these embodiments have been presented by way of example only, and are not intended to limit the scope of invention. Indeed, the novel apparatus and methods described herein may be embodied in a variety of other forms; furthermore, various omissions, substitutions and changes in the form of the apparatus and methods described herein may be made without departing from the spirit of the inventions. The accompanying claims and their equivalents are intended to cover such forms or modifications as would fall within the scope and spirit of the inventions.

What is claimed is:

1. An image forming apparatus, comprising:
a photosensitive drum;
an exposure component configured to expose the photosensitive drum based on image data;
a development component configured to form a toner image on the photosensitive drum with toner supplied from a toner cartridge;

15

a toner supply motor configured to supply the toner to the development component from the toner cartridge; and a processor configured to detect toner emptiness when a toner supply ratio calculated based on an integrated value of a pixel count value of the image data and an integrated value of a driving time of the toner supply motor is less than a preset threshold.

2. The apparatus according to claim 1, wherein the processor calculates the toner supply ratio based on the integrated value of the pixel account value in a predetermined processing section and the integrated value of the driving time of the toner supply motor.

3. The apparatus according to claim 2, wherein the processing section is a section determined in accordance with a predetermined number of prints.

4. The apparatus according to claim 2, wherein the processing section is a section determined in accordance with the integrated value of the pixel count value.

5. The apparatus according to claim 2, wherein the processing section is a section determined in accordance with the integrated value of the driving time of the toner supply motor.

6. The apparatus according to claim 1, wherein the processor calculates the toner supply ratio when toner near emptiness is detected based on the integrated value of the driving time of the toner supply motor.

7. The apparatus according to claim 1, further comprising: a toner density sensor configured to detect toner density of developer in the development component,

wherein the processor drives the toner supply motor when the toner density is less than a preset threshold, the processor detects the toner emptiness when the toner density is not recovered even when the toner supply motor is driven, and

the processor confirms the toner emptiness based on at least one of:

detection of toner emptiness which is based on the toner supply ratio, and

detection of toner emptiness which is based on the toner density.

8. A method of operating an image forming apparatus including a photosensitive drum, an exposure component that exposes the photosensitive drum based on image data, a development component that forms a toner image on the photosensitive drum with toner supplied from a toner cartridge, a toner supply motor that supplies the toner to the development component from the toner cartridge, the method comprising:

detecting toner emptiness when a toner supply ratio calculated based on an integrated value of a pixel count value of the image data and an integrated value of a driving time of the toner supply motor is less than a preset threshold.

9. The method according to claim 8, further comprising: calculating the toner supply ratio based on the integrated value of the pixel account value in a predetermined processing section and the integrated value of the driving time of the toner supply motor.

16

10. The method according to claim 9, wherein the processing section is a section determined in accordance with a predetermined number of prints.

11. The method according to claim 9, wherein the processing section is a section determined in accordance with the integrated value of the pixel count value.

12. The method according to claim 9, wherein the processing section is a section determined in accordance with the integrated value of the driving time of the toner supply motor.

13. The method according to claim 8, further comprising: calculating the toner supply ratio when toner near emptiness is detected based on the integrated value of the driving time of the toner supply motor.

14. The method according to claim 8, further comprising: detecting toner density of developer in the development component;

driving the toner supply motor when the toner density is less than a preset threshold;

detecting the toner emptiness when the toner density is not recovered even when the toner supply motor is driven; and

confirming the toner emptiness based on at least one of: detecting toner emptiness based on the toner supply ratio, and

detecting toner emptiness based on the toner density.

15. A toner emptiness detection system, comprising: a processor that detects toner emptiness when a toner supply ratio calculated based on an integrated value of a pixel count value of image data used to expose a photosensitive drum and an integrated value of a driving time of a toner supply motor that supplies toner to a development component from a toner cartridge to form a toner image on the photosensitive drum with toner is less than a preset threshold.

16. The toner emptiness detection system according to claim 15, wherein the processor calculates the toner supply ratio based on the integrated value of the pixel account value in a predetermined processing section and the integrated value of the driving time of the toner supply motor.

17. The toner emptiness detection system according to claim 16, wherein the processing section is a section determined in accordance with a predetermined number of prints.

18. The toner emptiness detection system according to claim 16, wherein the processing section is a section determined in accordance with the integrated value of the pixel count value.

19. The toner emptiness detection system according to claim 16, wherein the processing section is a section determined in accordance with the integrated value of the driving time of the toner supply motor.

20. The toner emptiness detection system according to claim 15, wherein the processor calculates the toner supply ratio when toner near emptiness is detected based on the integrated value of the driving time of the toner supply motor.
